BRAKE FOR PLANETARY DRIVES

Charles W. Howard, Franklin, Ohio

Application January 5, 1949, Serial No. 69,378

1. Claim. (Cl. 188-1)

This invention relates to new and useful improvements and structural refinements in torque converters, and the principal object of the invention is to provide what may be referred to as a tension regulating drive for winding devices, which will assure that the proper amount of tension is applied to a strip of material while it is being wound upon a roll, notwithstanding the progressively increasing diameter of the roll which is incident to the winding operation.

In particular, the invention is primarily intended for use in association with paper manufacturing or paper coating machines wherein a common source of power is employed for driving the machine as a whole and the winding device thereof, the invention being adapted to impart a positive, properly tensioned drive to the winding device regardless of the roll diameter, while the source of power or prime mover operates at a constant speed.

An important feature of the invention resides in the provision of means for pre-adjusting the tension which is to be applied to the material being wound, which means may be readjusted if required at any time during the winding operation.

Some of the advantages of the invention lie in its simplicity of construction, in its adaptability for versatile use in various branches of the torque converting art, and in its adaptability to economical manufacture.

With the above more important objects and features in view, and such other objects and features as may become apparent as this specification proceeds, the invention consists essentially of the arrangement and construction of parts as illustrated in the accompanying drawings, in which:

Figure 1 is a top plan view showing a portion of a paper making or paper coating machine including a winding device and illustrating the invention in association therewith;

Figure 2 is a side elevational view of the subject shown in Figure 1;

Figure 3 is a cross sectional view of the invention per se, and;

Figure 4 is a perspective view of a friction disc used in the invention.

Like characters of reference are employed to designate like parts in the specification and throughout the several views.

Referring now to the accompanying drawing in detail, the general reference character 10 designates a paper making or a paper coating machine of any conventional type, wherein a strip of

material 12 is processed by passing over a plurality of rollers 14, 16, etc. and travelling through a coating bath 18, or the like, so that eventually the finished product is delivered to a winding device 20 where it is to be wound upon a suitable spindle, or roll 22.

The machine 10 is driven by a suitable motor 24 through the medium of suitable gearing 26, and the instant invention assumes the form of a tension regulating drive designated generally by the reference character 28, which is employed for transmitting the torque from the motor 24 to the winding spindle or core 22.

The tension regulating drive 28 is contained in a suitable housing 30 which is provided with anti-friction bearings 32, 34 to accommodate a driven shaft 36 and a spindle 38 respectively, the driven shaft 36 being connected by means of a suitable coupling 40 to the winding shaft or spindle 22, as indicated in Figure 1.

A transversely extending partition 42 is provided in the housing 30 and is equipped with an additional anti-friction bearing 44 to accommodate the spindle 38, and it is to be noted that the inner end of the spindle 38 carries a still further bearing 46 which is mounted in a circular plate 48 formed integrally at the inner end of the driven shaft 36, whereby additional support for the latter is facilitated.

It should, of course, be understood that the shaft 36 and spindle 38 are axially aligned, and it is to be noted that an epicyclic gear train designated generally by the reference character 50 is provided for operatively connecting this shaft and spindle so that they may rotate at inversely proportional and variable rates of speed. This epicyclic gear train involves the provision of a case 52 which is rotatably mounted by means of anti-friction bearings 54, 56 on the driven shaft 36 and is provided with an internal, annular gear 58 meshing with a plurality of pinions 60 which, in turn, mesh with a further, central pinion 62 secured to the spindle 38. The pinions 60 are freely rotatable on suitable stub shafts 64 projecting laterally from the aforementioned plate 48, and it will be observed that the case 52 also carries an annular bevel gear 66 which meshes with a bevel pinion 68 secured to a drive shaft 70.

The drive shaft 70 projects outwardly from the housing 30 through a suitable bearing sleeve 72 and is operatively connected by a flexible coupling 74 to the motor 24. The driven shaft 36 and the spindle 38 are, of course, independently rotatable, and it will be apparent from

50 the drive shaft 70 projects outwardly from the housing 30 through a suitable bearing sleeve 72 and is operatively connected by a flexible coupling 74 to the motor 24. The driven shaft 36 and the spindle 38 are, of course, independently rotatable, and it will be apparent from

3

the foregoing that when rotation of the shaft 70 is imparted through the medium of the gearing 68, 66 to the epicyclic gear train 50, the epicyclic gear train will function in a differential manner, so to speak, so that the shaft 36 and the spindle 38 may be rotated at inversely proportional and variable rates of speed and any tendency to restrict the rotation of the spindle 38 will result in the transmission of correspondingly increased transmission of torque through the driven shaft 36.

It will be also apparent that by varying the restricting force on the spindle 38, the torque transmitted through the driven shaft 36 may be altered and the tension exerted by the winding spindle 22 on the material may be correspondingly regulated.

Therefore, means are provided for adjustably resisting rotation of the spindle 38, these means involving the provision of a pair of primary gears 76, 78 which are secured to the spindle 38 and constantly mesh with respective secondary gears 80, 82 which are freely rotatable and longitudinally slideable on a stationary countershaft 84. One end portion of this countershaft is securely pressed in a boss 86 provided on the aforementioned partition 42, and it is to be noted that the countershaft extends outwardly from the housing 30 through a bearing sleeve 88 and that the outer end portion of the countershaft is screw-threaded as at 90 to receive an internally screw-threaded hub 92 of an adjusting hand wheel 94.

The hub 92 of the hand wheel 94 is rotatably and slidably disposed in a suitable aperture formed in the bearing sleeve 88 and an end thrust bearing 96 is provided immediately adjacent the inner end of the hub, as is shown in Figure 3. A compression spring 98 is positioned on the outer, diametrically reduced portion 100 of the countershaft 84, one end of this spring pressing against the anti-friction bearing 96 while its remaining end bears against a pressure exerting member 102 which is slideable in an aperture 104 with which the housing 30 is provided.

If desired, a suitable oil seal 106 may be provided around the member 102, and in addition, removable grease retainers 108, 110 may be provided on the housing 30 in the region of the respective bearings 32, 34, as will be clearly apparent. The aforementioned secondary gears 80, 82 are freely and independently rotatable on the countershaft 84, this being facilitated by the provision of anti-friction bearings 112, 114 in the respective gears 80, 82, and a friction disc 116 is secured by suitable screws 118 to the gear 82, this being effected by providing the disc with a substantially large central opening 120 to freely accommodate the countershaft 84 and with a plurality of apertures 122 to receive the screws 118, as best shown in Figure 4.

The disc 116 is frictionally engageable with the remaining secondary gear 80, and a pair of end thrust bearings 124, 126 are disposed on the countershaft 84 between the gear 80 and the partition 42 and between the gear 82 and the pressure exerting member 102, substantially as shown in Figure 3.

It should be explained at this point that the ratio of the gears 76, 80 is different from that of the gears 78, 82, and since the gears 76, 78 are rigidly secured to the spindle 38 and rotate at the same speed, the gears 80, 82 are therefore driven at different speeds with respect of one to the other. To illustrate this point further, the gear

4

76 may have one more tooth than the gear 78, the gears 76 and 80 may have an equal number of teeth while the gear 82 may have one more tooth than either of the gears 76, 80, that is, two more teeth than the gear 78. This example of tooth arrangement is given, of course, for illustrative purposes only, since any gear ratios may be used. However, the example will serve to illustrate that the gear 80 will rotate at a faster speed than the gear 82 when the gears 76, 78 rotate in unison, and as a result, a certain amount of slippage will exist between the friction disc 116 and the gear 80, as will be readily apparent.

Accordingly, when rotation is imparted to the drive shaft 70 and the hand wheel 94 is loosened so that the spring 98 does not exert any substantial pressure to frictionally engage the disc 116 with the gear 80, the gears 80, 82 will be free to rotate at different speeds and the entire torque transmitted through the epicyclic gear train 50 will be delivered to the spindle 38 while very little effort, if any, will be made to rotate the driven shaft 36. However, as the hand wheel 94 is tightened and the amount of friction between the disc 116 and the gear 80 is increased, the frictionally controlled slippage between the disc and the gear 80 will tend to restrict the rotation of the spindle 38 and more and more torque will be delivered to the shaft 36 through the epicyclic gear train 50, in proportion to the tightening of the hand wheel 94.

In this manner, the amount of tension exerted upon the material 12 during winding may be varied as required by the grade, weight or condition of the material, this adjustment being either preset before the winding operation is commenced, or reset at any time during the progress thereof. However, in any event, the epicyclic gear train 50 will assure that proper tension of material is being maintained throughout the winding operation, notwithstanding the diameter of the roll which, of course, increases as the winding proceeds. In other words, the tension of the material is regulated automatically during the winding operation by the epicyclic gear train 50, while the purpose of the manual adjusting means controlled by the hand wheel 94 is to pre-adjust or readjust the tension in accordance with the physical characteristics of the material being wound.

It is believed that the advantages and use of the invention will be clearly apparent from the foregoing disclosure, and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

In a planetary gear type variable speed drive, the combination of a spindle, a stationary countershaft, a pair of primary gears secured to said spindle, a pair of secondary gears slideable and independently rotatable on said countershaft and meshing with the respective primary gears, the ratio of the meshing primary and secondary gears in one set being different from that in the other set whereby said secondary gears are rotated at different speeds, a friction disc secured to one of the secondary gears and engageable

with the other secondary gear, an end portion of said countershaft being screw threaded, and means for urging said secondary gears together, said means comprising a pressure exerting member slidable on the countershaft and engaging one of the secondary gears, a screw-threaded control element rotatable on the screw-threaded portion of the countershaft, and a compression spring interposed between said element and said pressure exerting member.

CHARLES W. HOWARD.
